UNITED STATES PATENT OFFICE.

THEODOR PUSKAS, OF BUDA-PESTH, AUSTRIA-HUNGARY.

SUBMARINE BLASTING.

SPECIFICATION forming part of Letters Patent No. 449,272, dated March 31, 1891.

Application filed June 14, 1890. Serial No. 355,472. (No model.)

To all whom it may concern:

Be it known that I, THEODOR PUSKAS, a citizen of the Kingdom of Austria-Hungary, and a resident of Buda-Pesth, Austria-Hungary, have invented certain new and useful Improvements in Submarine Blastings; and I declare the following to be a full, clear, and exact description of the same.

The boring of shafts for blasting under water is attended with extraordinary difficulties and a very considerable expenditure of time and money, while the effect of blasting without boring for shafts is varied in its significance, because the effect goes on after every operation.

My invention is illustrated in the accompanying drawing, which forms a part of this specification.

The idea of the proceeding is this: that at the precise moment when the cartridge, after having been carefully directed on the object to be blasted, shall explode, a corresponding pressure shall be felt from above, which shall concentrate the effect of the explosion of the cartridge at the bottom of and then upon the object to be blasted.

To meet any peculiarities of the place, the cartridge A may be lowered upon the object to be blasted either from the shore or from a suitable boat in the usual manner—that is, from a reel. This cartridge is protected by a bell-shaped or semi-spherical conical covering B, and is insured against falling out by wires. The object of the covering, which, as already mentioned, may be shaped in a variety of ways, according to the object to be blasted, and may, moreover, take the form of a simple disk, is by exerting a pressure from above (of which I shall speak presently) to attack the shell A more completely and also to transfer it to the object to be blasted. Precisely on account of the object for which it is designed, this covering B must be made of sufficiently massive and durable material, (of massive steel or iron, preferably,) and if this case is bell-shaped or conical it must be fastened to the horizontal or upward-bent rings C, in order that it may exert the effect of the upward pressure to better advantage. The case has in the middle of the top an opening whose wall is provided with a far-

reaching screw, and in this opening is placed the case D of the cartridge, and in the case the cartridge E itself. After the cartridge is put in the case, with which already the electric wires F have been connected, a plate D' is screwed upon the cover, the plate being provided with two holes in order that through them may be passed the circuit-wires. The wire F after leaving the covering-plate is directed to the spot where the blasting is to take place, which is sufficiently remote. The covering itself is in the direction of the plumb-line G, connected with a cartridge H, which cartridge stands at a correctly-calculated distance above the covering. The plumb-line falls immediately above this cartridge, and the end is wound on the reel.

The wires J, which conduct the electric current to the place of operation and which are connected to the cartridge H, run in the same direction as the wires F and ropes G. The cartridge H and the shell A are isolated from each other.

The wires F and J both run to the place of operation together from the one source of current, through which source they both receive the electric current at precisely the same moment and entirely independent of one another and conduct these currents, still independent of each other, to the proper cartridges, causing the explosion of the same.

With a suitably-constructed apparatus the operation is such that the wire J receives the sparks so much sooner and causes the shell H to explode, and the effect of this explosion is still going on when the shell A explodes. The interval is naturally very short; but the explosion can be made simultaneous, this depending upon the quality of the explosive matter.

From the directions and descriptions already given it follows, as a matter of course, that a more powerful force is exerted by the explosion of the cartridge after every operation. Under the effect of this pressure the covering or disk B remains upright at the very moment when the cartridge A, immediately beneath it, explodes, so that through these combined forces the effect of the cartridge A is limited by the effect of cartridge H. It first concentrates its own effect from

underneath the object to be blasted, and hence the effect will be increased in a wonderful measure.

It stands to reason that the strength of 5 the cartridge II, its distance from the cartridge A, and the solidity of the covering B must be so adjusted that the covering B shall not be destroyed through the explosion of the cartridge.

10 What I claim is—

The combination, in a submarine-blasting system, with the primary explosive having a superposed or surrounding covering, with

flanges or rings C, of a secondary explosive located above said primary explosive and 15 connected with said covering, and independently-controllable circuits to said primary and secondary explosives, substantially as described.

In witness whereof I have hereunto signed 20 my name in the presence of two subscribing witnesses.

THEO. PUSKAS.
